Primary Examiner — Elizabeth J Oswecki(74) *Attorney, Agent, or Firm* — Philip H. Burrus, IV(57) **CLAIM**

The ornamental design for an adjustable mask, as shown and described.

DESCRIPTION

FIG. 1 is a perspective view of an adjustable mask, showing my new design in an unadjusted configuration;
FIG. 2 is a left side elevation view thereof;
FIG. 3 is a right side elevation view thereof;
FIG. 4 is a rear elevation view thereof;
FIG. 5 is a front elevation view thereof;
FIG. 6 is a top plan view thereof; and
FIG. 7 is a bottom plan view thereof.
FIG. 8 is a perspective view thereof, shown in an adjusted configuration;
FIG. 9 is a left side elevation view thereof; and,
FIG. 10 is a top plan view thereof.
